THERAPEUTIC STRUCTURE

Edwin H. Tompkins, 1422 E. 6th St., Tucson, Ariz.

Filed May 10, 1957, Ser. No. 658,406

14 Claims. (Cl. 128—33)

This invention relates to therapeutic structures and is directed particularly to a device of this nature incorporated in or combined with the structure of a box spring designed to carry a standard mattress upon which a person may recline and a particular object of the invention is to provide improved means for giving therapeutic treatments to a person reclining on a mattress supported or carried by the structure.

In my prior patents, No. 2,345,438 and No. 2,425,655, I have incorporated a gyration creating device in an inner spring mattress, by which a person resting on the mattress will receive gyroscopic impulses that stimulate improved blood circulation and nerve relaxation in the person. Prior thereto vibration impulses, in contrast to gyroscopic impulses, had been imparted to mattresses and their supports, but vibratory impulses instead of being soothing and relaxing were in fact annoying to the person receiving them, and no material and effective stimulation of the blood circulation was observed. While the mattresses containing mechanism for creating gyroscopic impulses gave good results, certain vexatious problems were encountered in their construction and use. For example, mattresses are usually, if not always, enclosed, and since the gyroscopic are created by electric motors with axially unbalanced armatures or rotors mounted in free floating condition in a housing or support by resilient means, such as of elastic or resilient rubber, safety required the mounting of the motors and their housings in an exposed wall of the mattress where ventilation of the motor to the outside of the mattress was possible. This made it possible to eliminate heat from the motor and avoid fire hazards and damage to the mattress and motor. It was also difficult to distribute the gyroscopic impulses from the housing located in a side or end wall uniformly throughout the mattress while having the desired supporting softness or comfort in the faces of the mattress. Users also placed sheets and blankets over the walls in which the motors were located, that interfered with necessary ventilation of the motor.

An object of the invention is to provide a structure for delivering desired gyroscopic impulses to a person, which is simple, relatively inexpensive and practical and which is not open to the objections above discussed; with which a person receiving the gyroscopic impulses may recline upon a standard or any mattress of the degree of softness desired; with which the gyroscopic impulses will be distributed with uniform magnitude and effectiveness throughout the mattress across its entire face and hence to a person reclining thereon; which will decrease the cost of providing for the gyroscopic impulses; which will provide full and adequate ventilation of the motor and its housing in a manner where such ventilation will not be interfered with by blankets, sheets and other bedding and in which the motor will be easily accessible for any inspection or servicing that might be necessary.

A further object of the invention is to provide an improved box spring type structure having associated with it a more or less free floating gyration producing unit by which the gyroscopic will be distributed uniformly throughout the structure and to a mattress carried thereon.

It is another object of the invention to provide in a manner as hereinafter set forth a spring structure of the

2

character stated wherein the gyration producing mechanism is coupled in a novel manner with the springs of the structure so that the gyroscopic will be effectively transmitted from one spring to another.

5 Still another object of this invention is to provide in a manner as hereinafter set forth, a box spring structure having a gyroscopic unit suspended approximately in the central portion thereof upon the conventional springs whereby to transmit gyroscopic motion throughout the 10 structure for the purpose hereinbefore set forth.

Other objects and advantages will appear from the following description of one embodiment of the invention and the novel features will be particularly pointed out hereinafter in connection with the appended claims.

15 In the drawings:

Fig. 1 is a view of the underside or bottom of a box spring structure showing therein the gyroscopic unit and mounting means of the present invention;

Fig. 2 is a view looking at the central part of the top 20 of the box spring structure with the covering fabric partially broken away and showing the gyroscopic unit with the upper halves of the coil springs thereover;

Fig. 3 is a sectional view taken in a vertical plane approximately on the line 3—3 of Fig. 2 and showing 25 with the gyroscopic unit one of the supporting coupling rods which are attached to certain of the coil springs and which extend across the width of the box spring or transversely thereof;

Fig. 4 is a sectional view taken in a vertical plane substantially on the line 4—4 of Fig. 3, which plane of section extends longitudinally of the box spring structure across the gyroscopic unit supporting rods;

Fig. 5 is an enlarged detail view illustrating more 30 specifically the wire coil coupling two adjacent coil springs and supporting and showing in cross section one rod which extends axially through the coupling coil, the coil being in cross section and adjacent portions of the connected coil spring also being broken away or in section;

40 Fig. 6 is an exploded view illustrating one form of gyroscopic unit which may be employed for producing the desired gyroscopic;

Fig. 7 is an exploded view illustrating another form or embodiment of the gyroscopic unit;

45 Fig. 8 is a sectional detail taken substantially on the line 8—8 of Fig. 1 and showing a portion of the fabric material covering the top and sides of the box spring structure.

The invention is illustrated and will be described in 50 association with a conventional type of box spring such as is used on beds for the support of mattresses of the inner spring type or of other types. It is to be understood, however, that while a particular box spring construction is illustrated and described in the following body 55 of the specification, the invention is not limited to use only with this type of box spring but may be embodied in any type of separate spring structure employed to support any mattress or it may be embodied in a structure such as a sofa, lounge or the like, upon which a person may directly recline, so long as these structures are open 60 on the underside to permit desired ventilation of the gyration producing mechanism.

The box spring structure which is shown in Fig. 1 in bottom plan with the gyroscopic unit mounted therein, is 65 generally designated 10. This structure is shown as embodying a base frame made up of the longitudinally extending side rails 12 and transversely extending end rails 14, which rails usually are of wood. In addition to the side and end rails which are flat members, as shown in 70 Fig. 8 where one end rail only is illustrated in cross section, the box spring structure includes the spaced apart parallel bars or slats 16 which extend across the width.

of the structure and connect the side rails 12 together. Also there is a single central bar 18 which extends longitudinally of the box spring structure and connects together the transverse end rails 14 and in addition to this single central bar 18 the transverse end rails are connected by a multiplicity of heavy longitudinally extending wires 20.

Within the area defined by the longitudinal side rails 12 and the transverse end rails 14 there are supported upon and secured to the transverse slats 16 and the longitudinal wires 20 the conventional compactly arranged coil springs 21. These are, of course, the bottom ends of the coil springs which are secured to the slats 16 and wires 20 and any suitable means may be employed, as indicated at 22, for effecting the securement of the springs, such securing means being conventional and well known.

The top of the box spring structure is outlined and defined by a heavy wire frame 23 which is of rectangular form and of approximately the size of the outside dimensions of the bottom frame which is made up of the rails 12 and 14, the transverse and longitudinal slats 16 and 18 and the wires 20. This rectangular top frame 23 is secured in conventional manner as indicated at 23a to the adjacent outermost rows of the coil springs 21. Running across the width of the box spring in the plane of the heavy metal frame 23 are the conventional transverse helical wires 24 which lie between the transverse rows of the vertical coil springs 21 at the tops thereof and join the latter together.

The box spring structure is enclosed on its top and its ends and sides by a suitable fabric covering such as is conventionally employed and which covering is designated 25 and, as shown in Fig. 8, may be secured to the bottom frame, but this covering does not overlie the bottom side of the box spring structure as it is preferred that this remain open for complete ventilation of the gyratory unit hereinafter described.

In accordance with the present invention, in the central or approximately central area of the box spring structure a number of the upright coil springs have the lower halves thereof removed or cut away, thereby providing, as is clearly shown in Figs. 3 and 4, a space or area 26. In thus cutting away the lower halves of the selected centrally located coil springs the upper halves remain connected with the adjacent full or complete coil springs and are suspended in the upper part of the open area and these upper halves or upper portions of the coil springs are designated 21a.

Within the downwardly opening space or area there is supported, in the manner about to be described, a gyration producing unit which is generally designated 27. Two examples of such unit are illustrated in Figs. 6 and 7.

For the mounting of the gyration producing unit in the central area 26 of the box spring structure, the following means is employed.

It will be seen upon reference to Fig. 1, which shows the bottom or underside of the box spring structure, that the downwardly opening area 26 is bordered by two complete rows of springs 21 extending transversely or across the width of the box spring structure, which two complete rows of area bordering springs are each designated 33. Between these complete transverse rows 33 are two rows of springs which may be identified, for distinction from the rows 33, as interrupted transverse rows and these interrupted transverse rows are each designated 34. Also it will be understood that the interruption of these rows is brought about by reason of the inclusion therein of the cut-off or half springs 21a. It will be understood, of course, that the interrupted rows 34 are coupled together at the tops of the springs to the tops of the springs of the bordering rows 33 by the transverse helicals 24 and the tops of the adjacent complete springs 21 and the adjacent incomplete or half springs

21a are also coupled together by a transverse helical 24 as is clearly shown in Fig. 2.

Below the tops of the coil springs each of the transverse rows 33 is coupled for a distance on each side of the open area 26 with the complete coil springs of the adjacent interrupted row 34 by means of a pair of elongate coupling helicals or coupling springs 35. The connecting together or coupling of the springs of each row 33 with the adjacent full or complete springs of the row 34 by these coupling helicals 35 is effected by threading each pair of coupling helicals or springs 35 onto adjacent convolutions of the coils of the rows 33 and 34 so that the coupling pairs of helicals tie together the adjacent convolutions of the rows of springs 33 and 34. As stated, these tying or coupling helicals or springs 35 are located below the tops of the coil springs 21, preferably at about the second or third convolution down on each of the spring 21, as shown in Figs. 3 and 5. The two coupling springs 35 of each pair, which are in alignment across the width of the box spring structure, have spaced apart inner ends which are located approximately at the sides of the area 26.

Following the application of the two pairs of tie or coupling helicals or springs 35 to the adjacent rows 33 and 34 of the upright springs 21, there is extended axially of and through the two aligned coupling helicals 35 of each pair, a supporting or suspension rod 36 and these two rods bridge the area space 26 for supporting the gyratory unit 27 in the manner illustrated most clearly in Figs. 3 and 4.

After the supporting rods 36 have been inserted into the coupling or tying helicals 35, the two ends of each rod are turned down as indicated at 37 so as to prevent the rod from moving lengthwise through the tie springs. While the rods 36 have been shown as having the ends turned down to prevent the rods from shifting, any other suitable means may be placed on the rods for this purpose, if desired.

The gyration producing unit 27, as previously stated, is located in about the center of the box spring structure in the open area 26, and its sides are disposed adjacent to the rods 36 and the mounting plate 32 on each side of the housing is attached to the adjacent rod 36 in a suitable manner as, for example, the edge of the mounting plate may be rolled to form a sleeve around the rod 36 or other means can be used for securing the housing to the rods.

The housing 28 has mounted therein an electric motor by which the gyratory movement is given to the structure and which is generally designated 38 and which motor has an axially unbalanced rotor shaft for producing the gyrations of the motor and the parts connected thereto in the manner hereinafter set forth. This gyratory movement producing unit 27 is mounted upon the rods 36 with the axis of the rotor shaft directed transversely of the spring structure or in parallel relation with the transversely directed supporting rods.

In the structure shown in Fig. 6, one type of mounting for the electric motor is illustrated while in the structure shown in Fig. 7 another mounting means is shown.

In the structure of Fig. 6 the inner faces of the side walls 29 have secured thereto the upright channel members 39 in each of which is a channel strip 41 of highly resilient rubber. Extending across the bottom 40 of the housing between the upright highly resilient rubber strips 41 on the opposite side walls is a bottom highly resilient rubber strip 42.

The oppositely positioned rubber channels 41 have mounted therebetween and slidably engaged therein motor supporting bracket plates 43 each of which at its bottom edge rests on a bottom live rubber strip 42. These plates have their inner faces recessed as at 44 and in the center of each recess is an opening 45 for the extension through the plate of the adjacent end of the armature shaft 46 of the motor. The openings 45 are much larger than the shaft 46 to enable the shaft to move laterally in the openings 45.

Encircling each end of the body or the field coil encasing housing 47 of the motor, is an elastic rubber mounting cup ring 48 which fits in the adjacent bracket plate recess 44 and which has a central opening 49 aligning with the opening 45 of the bracket plate for the extension of the armature shaft therethrough.

Upon the outer or remote sides of the mounting plates 43 the armature shaft 46 of the motor has fixed thereto an eccentric weight 50 and outwardly from each of these off-center or off-balance weights the armature shaft has a fan 51 mounted thereon and fixed thereto.

The housing 28 may be closed in any suitable manner as by means of a removable top or cover 52, and elastic rubber strips 42' are disposed between the cover and the upper edges of the plates 43.

Fig. 7 shows a second form of gyration producing structure which in Figs. 1 to 4 is generally designated 27 and which reference character, of course, refers to both forms shown. In this second form of the gyration producing structure a housing or casing 53 is illustrated having side walls 54 and end walls, one only of which is illustrated and which is designated 55 and which walls have ventilation openings 56.

From the top part of each side wall extends a mounting plate 54a which is designed to be attached in the manner hereinbefore set forth to a rod 36 which is suspended on the vertical springs 21.

The numeral 57 generally designates a conventional type of electric motor to each end of the body of which is fixed a mounting adapter which comprises a circular plate 58 carrying the outwardly directed flange 59.

The numeral 60 designates the shaft of the motor armature and this passes through an elastic rubber mounting ring 61 which is carried on and encircles the flange 59. The ring 61 in turn is fitted into the circular band 62 forming a part of a mounting bracket plate 63 which carries four attaching lugs 64 disposed in rectangular arrangement to position in the housing 53 between the side walls 54 thereof to which they are secured by screws or in any other suitable manner.

The armature shaft 60 extends from each end of the motor body as will be readily understood, and each end of the shaft upon the outer side of the mounting bracket 63 has the eccentric or off-balance weight 65 fixed thereto and outwardly of each weight is fixed a cooling fan 66.

The electric motor in the gyration unit 27 is supplied with current through a twin cable 67, and is smaller than the housing so that by reason of its mounting in elastic rubber, the entire motor can gyrate in the housing.

It will be seen upon reference to Figs. 3 and 4, that the gyration producing unit 27, such as, for example, either the form shown in Fig. 6 or that shown in Fig. 7, is of an overall height materially less than the height of the upright coil springs 21 of the box spring structure and that when the unit 27 is attached by the mounting flanges or plates carried by the sides of the motor housing, to the supporting rods 36, it will be suspended within the area 26 and supported entirely by certain of the conventional vertical coil springs of the box spring structure in which it may be installed. Upon the operation of the motor in the housing, the eccentric weights attached to the motor armature will produce a gyroscopic motion of the motor in a small closed loop path in the housing and this motion will be imparted to the housing and through it to the supporting rods 36 and through them and the coupling tie springs or helicals 35 to the conventional coil springs 21. Since the coil springs 21 are all coupled together and the gyration producing unit is located in the central part of the box spring structure, it will be seen that the gyroscopic motion produced by the rotating eccentrically mounted weights will be evenly distributed from the center of the spring structure in all directions outwardly. Consequently a person resting on a mattress placed upon the structure will receive the de-

sired gyroscopic impulses and be soothed, relaxed and otherwise benefited by such motion.

The unbalanced rotor of the motor will cause the motor as an entity to move in a gyroscopic or closed loop path of small diameter, which is permitted by the elastic mounting of the motor in the housing. The motor, with its mass, upon gyrating will cause gyrations of the housing, and those gyrations will be distributed throughout all of the springs by reason of their interconnection to one another and to the housing. A mattress carried by the gyrating spring will receive such impulses and transmit the gyrations to a person resting on the mattress. This has been established by stroboscopic tests. Since the box spring structure is open on the lower side, air can freely circulate to the housing and motor, and avoid any danger of excessive heat, and no blankets or sheets used in making a bed on the mattress will interfere with this ventilation of the motor and its housing.

The approximately central disposition of the motor and 20 housing in the box spring frame will cause uniform distribution of the gyroscopic impulses to all parts of the spring and mattress. This enables any mattress of one's choice to be used, for maximum comfort, and still have the gyroscopic impulses delivered to a person resting on 25 the mattress.

While the gyroscopic unit has been illustrated and described as being directly in the center of the box spring frame and this is the preferred location, it may be disposed somewhat toward one or the other of the ends of 30 the box spring frame without impairing the efficiency of its action.

As will be readily apparent, by the removal of the lower halves of the springs 21 in the center of the box spring structure, leaving intact the upper halves, or portions 35 21a, the top surface continuity or evenness of the structure is maintained. Thus a mattress lying on the box spring will keep level or will be properly evenly supported throughout.

I claim:

40 1. A therapeutic structure comprising a supporting coil spring structure for a separate mattress and wherein such structure comprises a base frame, and an approximately horizontal, flexible top wall spaced above the base frame, a multiplicity of upright coil springs carried 45 by the frame below and supporting said top wall and coupled together in closely associated side-by-side relation, and a unit having an axially unbalanced rotary element disposed for rotation on a horizontal axis for creating gyroscopic impulses, a supporting housing for and 50 in which said unit is free to gyrate, there being an elastic medium between the unit and the housing for transmitting gyrations of the unit to the housing, the relationship of the springs being modified in the approximate center of the support to provide an open area, and 55 said housing being attached to certain of the springs intermediate of their ends, at opposite sides of said area and spaced from said frame and top wall and supported for relatively free floating motion in the area.

2. A therapeutic structure comprising spaced top and 60 bottom frames, a multiplicity of coil springs mounted between and coupled to the frames, said springs being arranged in two groups made up of a number of complete rows extending in one direction across the structure between opposite sides and a number of other rows parallel to the first rows and lying between the two groups, said other rows being interrupted in the bottom portions thereof substantially midway between their ends and providing with adjacent complete rows an open area approximately centrally of the structure, a pair of supports 65 disposed across opposite sides of said open area and attached to adjacent springs, and a gyration generating unit between and attached to said supports and suspended in said open area and functioning to transmit gyroscopic impulses throughout the structure.

70 3. A therapeutic structure comprising spaced top and

bottom frames, a multiplicity of coil springs mounted between and coupled to the frames, said springs being arranged in two groups made up of a number of complete rows extending in one direction across the structure between opposite sides and a number of other rows paralleling the first rows and lying between the two groups, said other rows being incomplete in the bottom portions thereof substantially midway between their ends and providing with adjacent complete rows an open area approximately centrally of the structure, a coupling means between springs of each of two incomplete rows and springs of one of said adjacent complete rows, an elongate support carried by each coupling means, said supports extending across opposite sides of said open area, and a gyration generating unit between and attached to said supports and suspended thereby in said open area and functioning to transmit gyroscopic impulses throughout the structure.

4. The invention according to claim 3, wherein the said coupling means is connected with convolutions of the coil springs of the respective coupled complete and incomplete rows between the middle and top ends of the springs.

5. A therapeutic structure comprising spaced top and bottom frames, a multiplicity of coil springs mounted between and coupled to the frames, the structure being of rectangular outline, said springs being arranged in two groups made up of a number of complete rows extending in one direction across the structure between opposite sides and a number of other rows paralleling the first rows and lying between the two groups, said other rows being incomplete substantially midway between their ends and providing with adjacent complete rows an open area approximately centrally of the structure, a coupling means between the springs of each of two incomplete rows and springs of one of said adjacent complete rows, the said coupling means comprising elongate spiral springs extending longitudinally of said rows of coil springs with certain of their convolutions encircling adjacent convolutions of the coil springs, elongate support members extending axially through the spiral springs, the support members extending across opposite sides of said open area, and a gyration generating unit between and attached to said supports and suspended thereby in said open area.

6. The invention according to claim 5, wherein said spiral springs coupling the coil springs terminate short of the sides of the frames and said support members comprise rods having means on their ends for preventing movement of the rods through the spiral springs.

7. The invention according to claim 5, wherein the said adjacent convolutions of the coil springs which are encircled by said certain convolutions of the spiral springs are between the middle and top ends of the coil springs.

8. The invention according to claim 5, wherein said unit embodies a housing and an electric motor therein having an armature shaft and an eccentric weight thereon to turn therewith and produce axial imbalance thereof, and the attachment of the unit embodies mounting plates integral with opposite sides of the housing and secured to the supports.

9. The invention according to claim 8, wherein said motor is positioned to have the armature shaft thereof directed transversely of the structure.

10. A therapeutic structure comprising a supporting coil spring structure for a separate mattress wherein in said structure there is a downwardly open base frame, a flat upper wall, a multiplicity of upright coil springs carried by the frame, the springs being coupled together in closely associated side-by-side relation and supporting said flat upper wall, and a unit having an axially unbalanced element rotatable about an axis parallel to said upper wall, for creating gyroscopic impulses, a housing in which said unit is supported for free gyration, there being an elastic medium between the unit and the hous-

ing for transmitting therapeutic gyrations of the unit to the housing, the relationship of the springs being modified to provide between them a small open spring free area, and means for attaching said housing to certain of the springs at opposite sides of said area and supporting the housing for relatively free floating motion in the area, as permitted by the springs to which the housing is attached.

11. The invention according to claim 10, wherein the last means includes spaced rods attached to the housing and extending in a direction horizontally and transversely of the structure.

12. A therapeutic device having a flat upper surface for supporting a separate mattress on which a person to be treated with gyroscopic impulses may be supported, said device comprising a downwardly open frame, coil springs supported side by side on and upstanding from said frame and articulately tied together and to the frame, a flexible sheet-like element disposed in a horizontal plane above and supported resiliently by said coil springs, and confined at its edges to said frame, a housing disposed between certain of said springs and below said element and spaced from both said frame and said element, means attaching said housing to a plurality of said springs at points intermediate of the ends of such springs, an electric motor with a rotatable shaft that has a substantial axial unbalance, disposed within said housing in spaced relation to all of the walls of the housing and with said shaft approximately horizontal, and resilient interponent means disposed between the walls of the housing and said motor and providing a resilient floating support for the motor in said housing, whereby when said motor is operated, its unbalanced shaft will cause the motor to gyrate bodily in said housing and through said interponent means cause said housing to gyrate and thereby transmit gyroscopic impulses from the housing through the springs to said element and anything supported on it, and heat from said motor will be dissipated downwardly through the open frame.

13. A therapeutic device having an approximately horizontal upper surface for supporting a separate mattress on which a person to be treated with gyroscopic impulses may be supported, said device comprising a box spring downwardly open at its lower surface and having as its upper surface an approximately horizontal, flexible, sheet-like element and as a support for said element a plurality of upright coil springs arranged side by side and articulately connected together to form a resilient unit, and electrically operated gyroscopic impulse creating means disposed within said box spring, below and spaced from said sheet-like element and floatingly supported by and between certain of said coil springs intermediate of their ends, said electrically operated means having a rotatable shaft axially unbalanced to a substantial extent disposed with its axis approximately horizontal, whereby the gyroscopic impulses created by said electrically operated means will be in a closed loop about said horizontal shaft axis and transmitted through said springs to said element and anything resting on it and heat from said electrically operated means may be dissipated through the said downward opening of the box spring by air circulation.

14. The device as set forth in claim 13, wherein said shaft axis is disposed in a direction crosswise of the length of the box spring.
